UNITED STATES PATENT OFFICE.

OLIVIER PIETTE, OF PARIS, FRANCE, ASSIGNOR TO SOCIÉTÉ ANONYME DES FOURS À COKE SEMET-SOLVAY & PIETTE, A CORPORATION OF BELGIUM.

HORIZONTAL COKING-OVEN.

1,386,799.

Specification of Letters Patent.

Patented Aug. 9, 1921.

Application filed November 6, 1918. Serial No. 261,423.

To all whom it may concern:

Be it known that I, OLIVIER PIETTE, of Brussels, Belgium, at present carrying on business at Paris, France, subject of the 5 King of the Belgians, have invented certain new and useful Improvements in Horizontal Coking-Ovens, of which the following is a specification.

The present invention relates to horizontal coking ovens with vertical flues and of the regenerative type arranged for heating with blast furnace or producer gas. In a certain class of ovens of the above type the checker work for one phase of the air preheating was situated in two arched chambers located under the ovens and to one side of the longitudinal battery center line and extending parallel to same and connected in series with one another by ducts, 20 the area of which was increased in order to obtain a suitable distribution of air to the retorts of the battery, in proportion to their distances from the chimney, and the checker work for the other phase was situated in two other arched chambers located on the opposite side of the battery center line and extending parallel to the same and connected in the same manner as the first mentioned pair.

30 The object of this invention is to provide means for operating regenerators, positioned as described above, in parallel instead of in series to enable both air and producer gas or blast furnace gas to be preheated.

35 Another object of this invention is to provide means for heating ovens with coke oven gas or producer gas or blast furnace gas or any combination of the same.

The annexed drawings illustrate the construction embodying my invention.

Figure 1 is a semi-vertical-longitudinal section through a pieddroit or flue base.

Fig. 2 is a transverse section of the oven through an air recuperator on line A—B of Fig. 1.

Fig. 3 is a transverse section of the oven through an air recuperator on line C—D of Fig. 1, and

Fig. 4 is a horizontal section through the recuperator galleries and the channels leading to the chimney.

In the following description primed reference numbers are employed to designate similar members or structure to those des-

ignated by the original numbers, but located 55 on the opposite side of the battery center line.

In the oven walls adjacent to the oven 1 are located a plurality of heating flues 2 and 2' which communicate by means of gas ports 3 and 3' with a plurality of gas chambers 4 and 4' located directly beneath them and into which coke oven gas is introduced by pipes *m* and *m'* provided with stop valves indicated by crosses on Fig. 1. One-half of 60 the chambers in each wall are fed with gas by means of pipes *m* and the other half by means of pipes *m'*.

Heating flues 2 and 2' communicate by means of twyters 5 and 5' with sole flues 70 located beneath the retorts which are divided transversely into halves 6 and 6' by means of walls 8 situated on the battery center line.

Underneath the sole flues and extending 75 at right angles to the same and parallel to the battery center line are located the regenerators *a* and *a'* and *b* and *b'*; alternate half sole flues 6 and 7 communicate with regenerators *b* and *a* respectively, half sole 80 flues 6 communicating with regenerator *b* by means of flue 9 controlled by damper 10 and half sole flues 7 with regenerator *a* by means of flue 16 which is controlled by a damper not shown but similar to damper 85 10; half sole flues 6' and 7' are connected in a corresponding manner with regenerators *b'* and *a'* respectively.

The regenerators *b* and *b'* and flues *g* and *g'* are divided by walls 11 and 11' in 90 such a manner that each chamber so formed communicates only with one sole flue 6 and 6' and flues *d* and *d'* respectively. In regenerators *a* and *a'* the checker work only is divided by walls 12 and 12' leaving a 95 flue under the crown of the arch of each chamber. Beneath the checker work of the regenerators *a* and *a'* are pairs of connecting arched flues *c* and *c'* extending parallel to the battery center line and connecting 100 with their respective regenerators *a* and *a'* by means of ports *f* and *f'* respectively which pierce the arched roof of said flues, said roofs supporting the checker work.

Flues *g* and *g'* connect with flues *d* and 105 *d'* located on opposite sides of the battery, but extending parallel to the longitudinal center line thereof, by means of flues *k* and

k' respectively. The cross sectional area of flues *k* and *k'* is increased in proportion to their distances from the chimney whereby a suitable distribution of the air (or gas as 5 will be explained later) is obtained. In the flues *k* and *k'* are placed valves or dampers *i* and *i'* respectively. Gas pipes provided with valves *h* and *h'* open into flues *k* and *k'*. Flues *c* and *c'* and *d* and *d'* opening into the chimney 13 through reversing valve *v* are provided with regulating dampers *r* for regulating the draft and special dampers *s* and *s'*. Reversing valve *v* is shown in Fig. 4 as a butterfly valve revolvable about a vertical axis through its center line so that it may also take the position shown by dotted lines in Fig. 4.

When heating with coke oven gas the device operates as follows:

20 Assuming that combustion is to take place in the heating flues on the left hand side (see Fig. 1) of the battery center line and coke oven gas to be used as the heating medium, reversing valve *v* being positioned as 25 shown by solid lines in Fig. 4, air is admitted to flues *d* and *c* through air inlet 14 and flues *d'* and *c'* are connected to the chimney. Valves *i* and dampers *s* and *s'* are open and valves *r* are set for the proper intensity of draft, and gas reversing cocks *h* and *h'* are closed, pipes *m* being open and pipes *m'* closed.

30 Air passes through the flue *d*, valves *i*, flues *k* and *g* into regenerators *b*, where it is preheated, flowing in parallel with another current of air which flows through the flues *c*, ports *f* into regenerators *a*, being likewise heated therein.

35 The air from regenerator *b* passing through port 9 enters sole flue 6 passing thence through twyvers 5 into the left hand group of combustion flues 2 in each of the side walls of its superimposed retort. Pre-heated air from regenerator *a* enters sole flue 7 through ports 16, passing thence into the left hand group of combustion flues 2 through twyvers 5 positioned opposite to those opening from sole flue 6. Coke oven gas is admitted to gas chambers 4 through pipes *m*, 40 from whence it issues through ports 3 into combustion flues 2 where it encounters the preheated air issuing from flues 6 and 7 through ports 5 and ignites. Rising through left hand flues 2 the products of combustion 45 enter horizontal flue 15 and pass to the right hand group of flues 2' in which they descend entering the sole flues 6' and 7' by means of twyvers 5' passing thence into their respective generators *a'* and *b'*. The products of 50 combustion entering the regenerator *a'* give up a portion of their heat to the same and escape through ports *f'* into flues *c'* and thence into the chimney. Similarly the products entering the chamber *b'* escape by 55 means of flues *g'*, *k'* and *d'* into the chimney.

ney. When regenerators *a'* and *b'* are heated sufficiently the currents of air and gas are reversed as follows:

Reversing valve *v* is positioned at right angles to its previous position, that is, in the position shown by dotted lines on Fig. 4. Air from the inlet 14 is now directed by reversing valve *v* into flues *d'* and *c'* passing from *d'* into regenerators *b'* through flues *k'* and *g'* and thence to combustion flues 2' 70 by means of twyvers 5'. Air from flues *c'* rises through ports *f'* into regenerators *a'* whence it passes to sole flues 7' and into the combustion flues 2' in the walls of the retorts located over the flues 7'. The products of combustion will follow a similar path to that previously described through regenerators *a* and *b*, heating the same, and will finally escape into the chimney.

When the retorts are to be heated by producer gas burned in the groups of combustion flues 2', the reversing valve *v* is positioned as shown by the dotted line in Fig. 4; dampers *s'* and *i'* are closed, dampers *s* and *i* being open. The valve in piping *h* 90 is closed and that in *h'* is opened. Air will now be heated in the regenerators *a'* and producer gas in regenerators *b'* whence they will pass to the combustion flues 2' where they will meet and ignite, the products of combustion heating regenerators *a* and *b* on their path to the chimney as previously 95 described. When the flow of air and gas is to be reversed dampers *s'* and *i'* are opened, the reversing valve is positioned as shown 100 by the solid lines in Fig. 4, dampers *s* and *i* being closed. The valve in piping *h'* is closed and the valve in piping *h* opened. Air will now be directed by valve *v* into regenerators *a* and gas will be admitted into 105 regenerator *b* through piping *h*, ducts *k* and *g*. Air and gas will meet in combustion flues 2 and the products of combustion will escape from the battery as previously described.

110 It is evident that when a combination of gases is to be employed for heating it is only necessary to admit coke oven gas on the same side as that on which blast furnace or producer gas is being admitted; the operation, otherwise, that is, in respect to the air for combustion and the disposal of the products of combustion, being the same as previously described.

Claims:

1. In a horizontal coking oven, in combination, a series of coking chambers, a series of combustion chambers, a pair of regenerators disposed perpendicularly to said chambers, a series of sole flues extending parallel to said chambers, alternate sole flues being connected with the same regenerator, a series of gas chambers, means for supplying gas to said gas chambers, each combustion chamber having connections with two 125

120

125

130

adjacent sole flues and with a gas chamber, means for supplying gas to one of said regenerators and means for supplying air to both regenerators, whereby it is possible to supply the combustion chambers with a richer gas from the gas chambers, and with air from both regenerators, or to supply them with a poorer gas through one regenerator and with air through the other regenerator.

2. In a horizontal coking oven, in combination, a series of coking chambers, a series of combustion chambers, a pair of regenerators disposed perpendicularly to said chambers, a series of sole flues extending parallel to said chambers, alternate sole flues being connected with the same regenerator, a series of gas chambers, means for supplying gas to said gas chambers, each combustion chamber having connections with two adja-

cent sole flues and with a gas chamber, the connection with the gas chamber being located between the connections with the sole flues, means for supplying gas to one of said regenerators and means for supplying air to both regenerators, whereby it is possible to supply the combustion chambers with a richer gas from the gas chambers, and with air from both regenerators, or to supply them with a poorer gas through one regenerator and with air through the other regenerator.

In witness whereof I have signed this specification in the presence of two witnesses.

OLIVIER PIETTE.
